Primary Examiner — Mark A Goodwin*Assistant Examiner* — Harold E Blackwell, II(74) *Attorney, Agent, or Firm* — CANTOR COLBURN LLP(57) **CLAIM**

The ornamental design for a panel for angle, as shown and described.

DESCRIPTION

FIG. 1 is a front-top-left perspective view of a panel for angle showing our new design;

FIG. 2 is a rear-top-right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion 9 in FIG. 1; and,

FIG. 10 is an enlarged view of the portion 10 in FIG. 2.

The dash-dash broken lines in FIGS. 1, 2 and 9, 10 are included for the purpose of depicting the partial enlarged views and form no part of the claimed design.

1 Claim, 6 Drawing Sheets(56)
